UNITED STATES PATENT OFFICE.

WILLIAM SAY, OF LONDON, ENGLAND.

BIT.

1,308,609.

Specification of Letters Patent.

Patented July 1, 1919.

Application filed December 4, 1916. Serial No. 134,984.

To all whom it may concern:

Be it known that I, WILLIAM SAY, a subject of the King of Great Britain, residing at London, England, have invented certain new and useful Improvements in Bits, of which the following is a specification.

This invention relates to that class of bit, auger or the like for use with an ordinary brace, lathe chuck or equivalent, having removable points and removable and adjustable cutting knives so that should the point get broken, or the blade broken or require sharpening, both can be removed and renewed instead of the whole bit being scrapped as is necessary with those having fixed points and blades.

My present invention consists of an improved construction of such devices and consists in constructing a bit for cutting circular holes in wood from a stem suitable for attachment to an ordinary brace or chuck, such stem having a hole in the end for securing a pointed rod with the point either eccentric or concentric to the rod and a boss or extension at the same end for carrying the cutting blade, both pointed end and blade being adjustable. The blade or knife may be so positioned that its cutting point or edge may be varied with regard to the center point within certain limits so that by this means holes of various diameters may be cut in addition to those effected by positioning the center point should the latter be eccentric to the rod.

My invention will be clearly understood from the following description aided by the annexed drawings in which:

Figure 1 is a front view of my improved bit, in which the blade is capable of being fixed solely in one position.

Fig. 2 is a side view of same, and

Fig. 3 a front view of the bit as applied to a sheet of wood.

Fig. 4 is a plan of the bit.

Fig. 5 is a front elevation of the bit, in which the blade can be fixed in varied positions.

Fig. 6 is a section on the line $\alpha\alpha$ of Fig. 5.

Fig. 7 is a back elevation of the bit shown in Fig. 5.

For the purpose of my invention and as shown in Figs. 1 and 2 I form the stem A of the bit with one end B shaped to fit the ordinary brace, chuck or equivalent, and in the other end and centrally of the stem a

vertical hole C is formed to receive a rod D having a point E at one end which projects the desired distance beyond the end of the stem A, the rod D being held in place by a set screw F inserted in a screw threaded hole in the stem and leading to the hole C therein.

Projecting from the stem A is an arm or boss G preferably having a downwardly projecting angular end H, and in this end a slot I is cut and therein is positioned the shank J of a knife K, the cutting edge L of which projects the desired distance, and to secure this knife K in place I employ a set screw M which is inserted in the outer end of the arm or boss and passes through the knife shank to hold it firmly in place.

By this construction the end wall N of the slot forms a backing and resistance to the knife K so that perfect cutting by the knife K, when revolved about the point in the usual manner, is insured.

In the modified structure shown by Figs. 5 to 7 I form at an angle to the stem A and across the face of the arm or boss G a slot P having a back wall Q in which I form two screw threaded holes for receiving screws R, S, the screw threads of the hole preferably extending into the side walls of the slot P for further grip of the screws R, S.

At or nearly at right angles to the slot P I form a hole C' leading from the hole C to the outer wall of the boss G, the hole C' leading through the slot.

I construct the shank J of the knife K with a hole J' and I also form the rear of the shank with reverse angular edge portions T, U, or bearing points for the screws R, S. When the knife shank J is inserted in the slot a pin V is passed through the hole C' in the boss G and the hole J' in the knife shank to hold the knife in the boss G. The screw holes for the screws R and S are formed centrally in relation to the slot P and, as a consequence, a portion of the screw threads is cut in opposite side walls of the slot as indicated in dotted lines by Fig. 6, it being easier from a practical construction to form these threaded openings completely through the arm or boss than only partially therethrough.

The point E in the construction shown by Figs. 5 to 7 is eccentric to the rod D and the latter is provided with two or more re-

cesses W at the part in alinement with the hole in the boss, one of which recesses is engaged by the pin V.

In assembling the appliance the rod D is first placed in the hole C and then the knife K is placed in its slot, the pin V is then passed through its hole in the boss and the opening in the knife K to provide a pivot for the latter and to engage one of the recesses W in the rod D. By operating the screws R, S the knife can be adjusted to the desired position, that is to say, the top screw R can be loosened and the lower screw S adjusted into the boss G to project the cutting edge of the blade forward to the desired degree and by reason of the knife being positioned at the angle the cutting edge or point will be positioned at a greater distance from the point E and vice versa. By tightening the screws R, S, the knife K will be secured in adjusted position and the pin V will also be tightly clamped in place and all the movable parts firmly held.

The adjustment of the knife K is not very extensive, and movement thereof outwardly from the boss will not turn the cutting edge to any appreciable degree away from a practical cutting position. In other words, the flat side of the blade will not be brought into an angular resisting position relatively to the circular line of cut described by the knife when rotated by the bit stem. The rod D with the eccentric point E can be turned in its opening or socket by loosening the pin V to bring the said point nearer to the blade, the said pin V being then caused to engage the recess W opposite that shown by Fig. 5. This adjustment of the rod will produce openings cut by the knife K of different sizes, and provides means with the adjustable knife to materially increase the range of adjustment.

What I claim is:—

1. A bit comprising a stem having a boss at its lower end extending at substantially a right angle thereto, the boss having an opening in its lower end in vertical alinement with the axis of the stem and also having a slot near its free end opening outwardly through one side thereof, a rod secured in said boss opening and having a

substantially straight pointed extremity, and a knife secured in said slot.

2. A bit comprising a stem having a boss provided with an extension arranged at substantially a right angle to the stem, said boss having a vertical slot opening outwardly through one side near the free end thereof and a vertical opening extending through its lower end in vertical alinement with the stem, a rod secured in said boss opening and having a substantially straight pointed free extremity eccentrically positioned relatively to the axis of the rod, a flat knife having a shank adjustably mounted in said slot, and means for securing the rod and knife, respectively, in the opening and slot.

3. A bit comprising a stem having a hole in its lower end for a pointed rod, a boss or arm having a slot cut at an angle to the stem and a hole at a right angle to said slot reaching to the hole in the stem, screws engaging the back wall of the slot, a knife having a hole in its shank and bearing portions for the screws, and a pin engaging the hole in the arm and passing through the hole in the shank of the knife and engaging the rod, the screws engaging said bearing portions and serving to secure the knife and pin in fixed positions.

4. A bit comprising a stem having a hole in its lower end, a pointed rod having its point eccentric to the axis of the rod, a boss or arm having a slot cut at an angle to the stem and a hole at a right angle to said slot reaching to the hole in the stem, screws engaging the back wall of the slot, a knife having a hole in its shank and bearing portions for the screws, a pin engaging the hole in the arm and passing through the hole in the shank of the knife and engaging the rod, the screws engaging said bearing portions and serving to secure the knife and pin in fixed positions.

In testimony whereof I have hereunto set my hand in presence of two subscribing witnesses.

WILLIAM SAY.
